(57) **CLAIM**

The ornamental design for a gaming machine, as shown and described.

DESCRIPTION

FIG. 1 is a front right front perspective view of a gaming machine showing our new design;

FIG. 2 is a top view thereof;

FIG. 3 is a front view thereof;

FIG. 4 is a right side view thereof;

FIG. 5 is a rear view thereof; and,

FIG. 6 is a left side view thereof.

The broken lines depicting the remainder of the gaming machine illustrates environmental structure and form no part of the claimed design. The curved oblique line shading shows that the surface is a transparent, translucent, highly polished or reflective surface.
